US00D969148S

(12) **United States Design Patent** (10) Patent No.: **US D969,148 S**
(45) Date of Patent: ** Nov. 8, 2022

(54) **DISPLAY SCREEN WITH GRAPHICAL USER INTERFACE**

(71) Applicant: **Google LLC**, Mountain View, CA (US)

(72) Inventors: **Masumi Matsumoto**, Kirkland, WA (US); **Adam Rodriguez**, Singapore (SG); **Thomas Horn**, Singapore (SG); **Bin Zhu**, Norcross, GA (US); **Xiaowen Karen Zhang**, Singapore (SG); **Yohan Launay**, Singapore (SG)

(73) Assignee: **Google LLC**, Mountain View, CA (US)

(**) Term: **15 Years**

(21) Appl. No.: **29/746,937**

(22) Filed: **Aug. 18, 2020**

Related U.S. Application Data

(63) Continuation of application No. 29/622,347, filed on Oct. 17, 2017, now abandoned.

(51) **LOC (13) Cl.** **14-04**

(52) **U.S. Cl.**

USPC **D14/486**

(57) **CLAIM**

The ornamental design for a display screen with graphical user interface, as shown and described.

DESCRIPTION

The sole FIGURE is a front view of a display screen with graphical user interface, showing our new design.

The broken lines of uneven length show the display screen and form no part of the claimed design. The broken lines of even length show portions of the graphical user interface that form no part of the claimed design.

1 Claim, 1 Drawing Sheet
